DESIGN FOR A GAME BOARD

Lillian Streib, Stratford, Conn.

Application March 2, 1946, Serial No. 127,045

Term of patent 7 years

(Cl. D34—5)

To all whom it may concern:

Be it known that I, Lillian Streib, a citizen of the United States, residing in the town of Stratford, county of Fairfield, and State of Connecticut, have invented a new, original, and ornamental Design for a Game Board, of which the following is a specification, reference being had to the accompanying drawing, forming part thereof.

The figure is a plan view of a game board, showing my new design.

The board and spinning arrow are of conventional thickness.

I claim:

The ornamental design for a game board, as shown and described,

LILLIAN STREIB.
